6-ETHYLMETHYLAMINO-5-METHYL-4,4-DIPHENYL-HEXAN-3 ONE

Eric Walton, London, England, assignor to Burroughs Wellcome & Co. (U. S. A.) Inc., Tuckahoe, N. Y., a corporation of New York

No Drawing. Application January 29, 1952,
Serial No. 268,907

Claims priority, application Great Britain
February 12, 1951

3 Claims. (Cl. 260—570.8)

This invention relates to improvements in or relating to diphenyl ketones of pharmaceutical value and to a method for the preparation thereof.

The compound *dl* - 6 - dimethylamino - 4,4 - diphenylheptan-3-one (referred to frequently under the name "amidone") having the following formula:

is known to have analgesic activity. Various analogs of this compound are also known and their analgesic activity, compared with "amidone" itself is discussed in *Nature*, volume 159, page 679, dated May 17, 1947, where it is shown that these known analogs are of poor analgesic activity. It was subsequently reported that *l*-amidone has about twice the activity of morphine (*Nature*, volume 160, page 65, dated November 1, 1947).

Various other compounds of this general type have been prepared and while some possess advantages at least as regards specific test animals, none has hitherto been found generally superior to "amidone." As a rule the reaction sequence leading to the formation of compounds of the "amidone" type results in mixture of two isomers, I and II.

Mixtures can be avoided either before the last step of the reaction sequence (addition of EtMgBr to the appropriate nitrile) by separation of the isomeric nitriles, or, after the reaction, through the fact that the ketimides corresponding to type II, are less rapidly hydrolyzed than those corresponding to type I.

It has now been found that the compounds 6-ethylmethylamino-5-methyl-4,4-diphenylhexan-3-one (Formula III) and 6 - ethylmethylamino-4,4-diphenylheptan-3-one (Formula IV) or salts thereof such as the hydrobromide, hydriodide etc. also exhibit valuable analgesic properties comparable to those of "amidone" but with less marked concomitant side effects.

This freedom from side effects is especially notable in dogs. It is well known that "amidone" produces nausea, vomiting and other digestive disturbances in dogs in the dose range required for analgesia. The compounds of the present invention do not produce such effects, although their analgesic potency is at least equal to that

2

of "amidone," and therefore, are of value in veterinary medicine.

The present invention therefore comprises, as pharmaceutical substances exhibiting improved analgesic properties, the compounds 6-ethylmethylamino-5-methyl-4,4-diphenylhexan-3-one and 6-ethylmethylamino-4,4-diphenylheptan-3-one. These compounds may be produced by any suitable synthetic routes.

The compounds of the present invention may be presented as salts with such acids as are not toxic at the dose level at which the compound is to be administered.

The following examples illustrate the invention.

All temperatures are given in degrees centigrade.

EXAMPLE 1

Preparation of 6 - ethylmethylamino - 5 - methyl-4,4-diphenylhexan-3-one

25 Ethylmethylamine (160 g.), boiling point 34-36°, and β -propylene oxide (160 g.) were heated in a closed vessel at 140° for 2 hours. After 16 hours the product was distilled and the fraction boiling at 140-144° collected; this consisted of *l*-ethylmethylamino-2-propanol. The later (300 g.) dissolved in dry chloroform (250 ml.) was slowly added to a stirred solution of thionyl chloride (218 ml.) in more chloroform (900 ml.). After 24 hours at room temperature the chloroform and hydrogen chloride were removed in vacuo and the residue treated with 35 excess dilute alkali and extracted with ether. The dried ethereal extract on distillation yielded *l*-ethylmethylamino-2-chloropropane as an oil, boiling point 35-38°/22 mm. (yield 268 g.).

The whole of this base was added over 1 hour to a 40 stirred solution of diphenylmethylcyanide (422 g.) in dry benzene (1500 ml.) under gentle reflux and containing sodamide (99 g.) in suspension. After refluxing for a further 2 hours the product was decomposed with water and the benzene and ether extracts shaken with dilute hydrochloric acid. The acid layer with alkali gave a basic oil which on extraction with ether and distillation yielded a fraction (408 g.) boiling point 140-150°/0.01 mm. consisting mainly of a mixture of 3-ethylmethylamino-1,1-diphenylbutyl and 3-ethylmethyl-2-methyl-1,1-diphenylpropyl cyanides.

45 50 This mixture of bases was dissolved in dilute hydrochloric acid, washed with ether to remove traces of non-basic oil, and evaporated to dryness. The residue dissolved in alcohol-ether gave early crops, which on recrystallization from the same solvent afforded pure hydrochloride of 3-ethylmethylamino-2-methyl-1,1-diphenylpropyl cyanide, melting point 222-224°.

In order to isolate the isomeric cyanide in pure form,

55 the oily base, obtained from the hydrochloride mother liquor by treatment with alkali, was converted to the hydrobromide (as described above for the hydrochloride). The hydrobromide, on crystallization from alcohol, gave pure 3-ethylmethylamino-1,1-diphenylbutyl cyanide hydrobromide, melting point 150-155°.

3 - ethylmethylamino-2-methyl-1,1-diphenylpropyl cyanide (10 g.) (from its hydrochloride) in dry ether was added to an ethereal solution of ethyl-magnesium bromide prepared from magnesium (2.5 g.) and ethylbromide (7.8 ml.). Dry xylene (50 ml.) was added, and after removal of the ether by evaporation the mixture was refluxed for 5 hours, whereupon a brownish-green adduct slowly separated. The product was decomposed with

alkali (yellow to indigo-carmine), evaporated to dryness and extracted with ether. The ethereal extract was shaken with dilute hydrobromic acid and the acid extract refluxed for 2 hours, washed with ether and then evaporated to dryness. As the residue failed to give a crystalline hydrobromide it was converted to base, which was distilled at 135-146°/0.05 mm. This distillate with oxalic acid gave the acid oxalate of 6-ethylmethylamino-5-methyl-4,4-hexan-3-one, which crystallized from alcohol in hexagonal prisms, melting point 179-182°; and with hydroiodic acid, the hydriodide of the same ketone, which crystallized from alcohol-ether in needles, melting point 199-202°.

EXAMPLE 2

Preparation of 6 - ethylmethylamino-4,4-diphenylheptan-3-one

3-ethylmethylamino-1,1-diphenylbutyl cyanide (from its hydrobromide) (146 g.) in dry ether was added to an ethereal solution of ethylmagnesium bromide prepared from magnesium (36.4 g.) and ethyl bromide (114 ml.). Dry xylene (250 ml.) was then added and the ether allowed to evaporate. The mixture was refluxed for 7 hours, during which time the adduct slowly separated. The product was decomposed with alkali (yellow to indigo-carmine), evaporated to dryness and well extracted with ether. The ethereal extract was shaken with dilute hydrobromic acid and the acid extract boiled for 5 hours, washed with ether and evaporated to dryness in vacuo.

Treatment of this residue with water gave a small amount of 6-ethylmethylamino-4,4-diphenylheptan-3-one hydrobromide, which on further crystallization from water formed tablets, melting point 193-195°, but most of the ketone was isolated as follows:

The aqueous mother liquors were made alkaline and the total base extracted with ether and fractionally distilled. The earlier fractions, boiling point up to 200°/7 mm., were found to contain a by-product, but that boiling at 200-215°/7 mm. with dilute hydrobromic acid afforded 6 - ethylmethylamino-4,4-diphenylheptan-3-one hydrobromide, which was purified by recrystallization from water.

I claim:

1. A member of the class consisting of a free base and acid addition salts thereof with non-toxic acids, said free base possessing the formula

2. 6-ethylmethylamino-4,4-diphenylheptan-3-one.
3. A nontoxic acid-addition salt of 6-ethylmethylamino-4,4-diphenylheptan-3-one.
